United States Patent

Des. 240,095
Patented June 1, 1976

240,095

TOOTHBRUSH

Arnold Sims, Beachwood, Ohio, assignor to
Vistron Corporation, Cleveland, Ohio

Filed Apr. 10, 1974, Ser. No. 459,552

Term of patent 14 years

Int. Cl. D4—02

U.S. Cl. D4—15

FIG. 1

FIG. 2

FIG. 3

FIG. 4

FIG. 5

FIG. 1 is a front perspective view of a toothbrush, showing my new design;

FIG. 2 is a plan view;

FIG. 3 is a front elevation of FIG. 2;

FIG. 4 is a right-end elevation of FIG. 3; and

FIG. 5 is an oblique elevation taken along line 5—5 of FIG. 3 and looking in the direction of the arrows.

The portion of an electric toothbrush handle which is shown in broken lines in FIG. 1 is for illustrative purposes only and forms no part of the claimed design.

I claim:

The ornamental design for a toothbrush, as shown and described.
